UNITED STATES PATENT OFFICE.

ARTHUR H. FLEET, OF MILWAUKEE, WISCONSIN, ASSIGNOR TO THE CUTLER-HAMMER MFG. CO., OF MILWAUKEE, WISCONSIN, A CORPORATION OF WISCONSIN.

CAP FOR LAMP SOCKETS AND THE LIKE.

Application filed September 13, 1920. Serial No. 410,001.

This invention relates to caps for lamp sockets and the like.

An object of the invention is that of providing an improved and concealed securing means for such caps and the like adapted to operate automatically and with increasing effectiveness as the parts are screwed into attachment with a standard fitting in the usual manner.

10 A further object is that of providing simple and efficient securing and locking means for the foregoing purposes comprising a minimum number of detached parts, such parts being moreover capable of ready and 15 economical manufacture and being adapted to repeated use.

Other objects and advantages will hereinafter appear.

The accompanying drawing illustrates 20 certain of the forms which the invention may assume in practice and the same will now be described, it being understood that the invention is capable of embodiment in other forms falling within the scope of the 25 appended claims.

In the drawing,

Figure 1 is a vertical sectional view illustrating a proposed construction and arrangement, the parts thereof being separated;

Figs. 2 and 3 are similar views illustrating slightly modified structures; while

Fig. 4 is a top plan view of the lamp socket cap illustrating more fully certain 35 details of Fig. 2.

Referring to Fig. 1 of the drawing, the same illustrates a cap 9 for lamp sockets and, the like, said cap having a rigidly secured and internally threaded tubular bushing 40 10 adapted to fit a relatively fixed and exteriorly threaded standard nipple indicated at 11, such standard nipple being provided exteriorly with a circumferential shoulder 12 located beyond the threaded portion 45 thereof. The bushing 10, which is of material thickness, is provided at its end remote from the cap proper with an annular recess 13, said recess having preferably a circumferential wall substantially coaxial with the bushing and with a transverse wall substantially perpendicular to the axis of the bushing, said latter mentioned wall constituting 50 an internal shoulder substantially parallel to the shoulder 12 of the nipple.

55 A lock washer 14 of usual construction is

located within the recess 13 and adapted to securely yet releasably lock the aforesaid parts in assembled relation and under such conditions to be substantially enclosed and concealed therebetween and with 60 in the bushing.

For convenience in handling, the lock washer is preferably permanently retained within the recess 13 and as illustrated in Fig. 1, such retention is attained by making 65 the diameter of such recess slightly less than the outer diameter of said lock washer when fully expanded radially. Said washer is thus adapted to be sprung within said recess and to be thereafter firmly yet 70 removably retained therewithin with its parts in suitable operative position.

As illustrated in Figs. 2 and 3, the recess 13 is formed slightly larger than the normal diameter of the lock washer to permit 75 radial expansion of the latter as the same is compressed between the adjacent shoulders of bushing 10 and nipple 11. Retention of the washer within the recess is effected in the construction of Fig. 2 by striking in the edge portion of the bushing at circumferentially spaced points 15 in advance of the washer thus providing against accidental removal or displacement of the washer. In the construction of Fig. 3, a 80 narrow flange or burr 16 of the bushing material is spun inward about the lock washer for retention of the latter, said flange or burr being moreover interrupted as indicated at 17 to permit forward and outward 85 projection of the end of said washer which directly coacts and interlocks with the nipple 11.

The foregoing construction and arrangement thus provides a very serviceable and 90 effective concealed locking device for the foregoing elements, said device being moreover adapted to perform its intended functions when the cap is simply screwed home upon the nipple in the usual manner. Further, the aforescribed locking means is 95 especially advantageous in those cases where a socket cover or husk is employed, in which case obviously the inner marginal portion of the husk is interposed between the lock 100 washer 14 and the shoulder 12, since the entire operation of assembling and locking the cap in place may be performed from a position substantially in axial alignment with 105 said elements. The device is thus markedly 110

superior to the ordinary set screw lock heretofore employed, such set screw obviously requiring actuation from a radial direction and being therefore inherently incapable of use in conjunction with certain types of husk.

The device possesses the further advantage of having no small detached parts which are capable of becoming separated 10 from the principal elements, the lock washer being as aforescribed permanently retained within its recess and thus protected against displacement or loss.

What I claim as new and desire to secure 15 by Letters Patent is:

1. A lamp socket cap having a threaded bushing rigidly secured thereto, an annular recess in said bushing adapted to receive a split washer, the terminal portions of said 20 washer being oppositely disposed out of the plane thereof, and a shouldered support upon which said bushing is adapted to be threaded, said washer permitting relative rotary movement of said support and bush-

ing in one direction while locking the same 25 against such movement in the opposite direction.

2. The combination with a lamp socket cap having a threaded bushing and a fitting to receive said bushing, said bushing 30 and said fitting being provided with opposed shoulders, of an oppositely toothed lock washer to be clamped between the shoulders of said bushing and fitting for securely and releasably locking the same in 35 assembled relation, said washer and said bushing having cooperating parts to resist separation thereof.

3. A lamp socket cap having one end of a threaded bushing rigidly secured thereto, 40 the opposite end of said bushing being provided with an annular recess, and a split washer having a terminal tooth engaging a wall of said recess and an opposite terminal tooth extending outwardly from said recess. 45

In witness whereof, I have hereunto subscribed my name.

ARTHUR H. FLEET.
